DESIGN FOR A LAPEL PIN

Lawrence P. Bosworth, Westport, Conn.

Application June 27, 1940, Serial No. 93,290

Term of patent 3½ years

To all whom it may concern:

Be it known that I, Lawrence P. Bosworth, a citizen of the United States, residing at Westport, in the county of Fairfield and State of Connecticut, have invented a new, original, and ornamental Design for a Lapel Pin, of which the following is a specification, reference being had to the accompanying drawing, forming part thereof.

I claim:

The ornamental design for a lapel pin, as shown.

LAWRENCE P. BOSWORTH.
